UNITED STATES PATENT OFFICE.

NATHANIEL COLVER, OF DETROIT, MICHIGAN.

BOOT AND SHOE.

Specification of Letters Patent No. 11,662, dated September 12, 1854.

To all whom it may concern:

Be it known that I, NATHANIEL COLVER, of the city of Detroit and county of Wayne and State of Michigan, have invented a new and Improved Method of Manufacturing 5 Boots and Shoes; and I do hereby declare that the following is a full and explicit description thereof, reference being had to accompanying drawings and to letters of reference marked thereon.

The nature of my invention consists in the substitution of wood for sole leather in the construction of a boot or shoe, and the manner of uniting the same with the upper 15 leather in its construction.

In constructing a boot or shoe, I take a piece of such firm and durable wood as I choose and carve it into the perfect shape of the entire bottom of the boot or shoe. See 20 Figure 1. The upper side, (or place of the inner sole, if the boot were made of leather) I scoop out so as to sit natural and easy to the bottom of the foot. See letter A, Fig. 1. Around the upper and outer edge of it, I 25 cut a groove or rabbet (except in the shank) about three eighths of an inch deep, and in width according to the thickness of the upper leather to be used. See letter B, Fig. 1. In the shank I cut the rabbet or groove the 30 same as elsewhere, only I extend the rabbet around the edge of the sole and partially on to its bottom. See letter C, Fig. 1. The heel of the boot or shoe is carved upon the same piece of wood extending downward. 35 See letter D, Fig. 1. The piece or bottom thus carved is then made fast to an ordinary last by means of a screw driven through the last and attaching it to the same. The upper leather of the boot or shoe is then, as it is 40 called, lasted—that is, drawn over the last

and the edges carefully fitted so as to rest upon the groove or rabbet (save in the shank) where it is fastened with nails. See letter A, Fig. 2. In the shank a projection of the leather is made to extend around the 45 edge partially upon the bottom, where, in addition to the regular course of nails with which it is fastened all around, another row (more or less) of nails is added. See letter B, Fig. 2. The object of this extension and 50 additional fastening in the shank is to give firmness and strength at this part of the boot or shoe, where the greater part of the strain comes. By this method, I get a boot or shoe for the mechanic, farmer or laboring 55 man of equal comfort to the foot and of far greater durability than the ordinary kind, and moreover, it is a perfect safeguard to the foot from harm, and especially from water—against the latter it is a perfect defense.

I do not claim the use of wood, as soles, or bottoms of boots or shoes, as used by the peasantry of France or Germany, when worn as sandals or shoes, made entirely of 60 wood, and I hereby disclaim any such pretension; but

What I do claim as my invention and desire to secure by Letters Patent, is—

The construction of boots and shoes, (with 70 uppers as now constructed in the United States) with a wooden instead of a leather sole, or bottom, attached to the leather uppers, as above described, or in any equivalent manner, for the purpose above set forth. 75

NATHANIEL COLVER. [L.S.]

In presence of—

Wm. A. MOORE,
T. S. BLACKMAR.
